UNITED STATES PATENT OFFICE

2,125,959

CUTTING MACHINE

Thomas H. Seely, Melrose, Mass., assignor to
United Shoe Machinery Corporation, Paterson,
N. J., a corporation of New Jersey

Application September 30, 1936, Serial No. 103,399

12 Claims.

(Cl. 12—40)

This invention relates to cutting machines and is herein illustrated as embodied in a machine for making a cut in a locality in the shank portion of a sole which is designed to be used in practicing the method of United States Letters Patent No. 2,008,071, granted July 16, 1935, upon an application filed in the name of John B. Hadaway.

The patent discloses a method of producing shoes having so-called close shanks, that is shoes having a transversely convex bottom in which the edges of the shank portion of the sole lie close to the adjacent upper, said shank portion having substantially no tendency to contract and thereby cause said edges to separate from said upper. In carrying out the method, use is made of a sole having in its shank portion a longitudinal gouge and a flap or tongue which is the counterpart of the gouge and is hinged to the sole along one edge of the gouge, the illustrated machine being particularly designed to produce such a tongue and gouge in a sole or other piece of sheet material.

According to one feature of the invention, there are provided a knife and a pair of feed rolls shaped to distort the blank by forming a bulge in it and arranged to feed it to the knife in such manner that one end of the edge of the knife enters the blank, remains in it until the gouge and tongue are substantially completed and then emerges from the blank, the other end of the edge of the knife being maintained at all times outside the blank.

It is desirable to provide means for properly presenting a blank to the rolls. To this end, according to another feature of the invention, a feed table which presents the blank to the rolls is provided with a pair of gages which are normally open to receive a blank between them, are closed by the depression of the starting treadle of the machine and locked in closed position, and are unlocked after the rolls have gripped the blank.

These and other features of the invention including certain details of construction and combinations of parts will be described as embodied in an illustrated machine and pointed out in the appended claims.

Referring to the accompanying drawings:

Fig. 1 is a side elevation of a machine in which the present invention is embodied;

Fig. 2 is a perspective of a sole after it has been operated upon;

Fig. 3 is a plan view of a portion of the machine showing in dot-and-dash lines a sole in the

position which it occupies before the gages close upon it;

Fig. 4 is a vertical section through the work-engaging parts of the machine showing a sole 100 in the same position in which it is shown in Fig. 3;

Fig. 5 is a section similar to Fig. 4 but showing the sole in process of being operated upon;

Fig. 6 is a section on the line VI—VI of Fig. 1 showing more particularly the mounting of the slide member or trip which releases the pawl 93;

Fig. 7 is a front elevation of portions of the two feed rolls showing in section a sole being operated upon;

Fig. 8 is a section on the line VIII—VIII of Fig. 3 showing only the top of the table, the adjustable block and the stem of the end gage which is slidable in this block; and

Fig. 9 is a detail in elevation showing the mounting of the slide member or trip 107 and its relation to the upper end of the push rod 103.

The general construction of the machine is like that of the machine of United States Letters Patent No. 1,382,689, granted June 28, 1921, upon an application filed in the name of William C. Stewart; and before describing the new construction, the old construction will be briefly described.

Located near the front of the machine (the left-hand end as viewed in Fig. 1) are two rolls 11 and 13 the shapes of which differ from those of the patented machine, since the present machine is designed to produce a weakened locality in the shank of the sole 100 by forming a gouge 200 and a flap 300, while the patented machine is de-

signed to skive the opposite edges of the shank portions of soles. These rolls are brought to rest, as shown in Fig. 4, with a gap between them.

The operator thrusts a sole, heel end foremost, between the rolls until the heel end of the sole contacts with a gage 15 the stem of which is longitudinally adjustable in a slot 17 (Fig. 3) in a block 19 which is adjustable toward and from the rolls and may be so adjusted by turning a hand wheel 21 located at the front of the machine.

The block 19 (Figs. 1, 8) is adjustably mounted in a table 23 which is pivotally supported upon the upper ends of four substantially upright parallel links two of which are indicated at 25.

After the sole has been thrust through the gap between the rolls and its heel end caused to contact with the heel-end gage 15, a treadle 27 (Fig. 1) is depressed, whereupon the rolls start to rotate in the directions indicated in Fig. 4, and the links 25 are swung to the left (Fig. 1) carrying

with them the table 23 upon which the rear part 35

50

55

55

of the sole rests. The table, which moves in timed relation with the rotation of the rolls, continues its movement to the left until the rolls have properly gripped the sole and is then returned by the links to the position shown. The rolls continue their rotation thus causing the sole to be cut by the stationary knife 28 (Figs. 1, 5). As thus far described, with the exception of the shapes of the rolls 11 and 13 and the block 19, the machine is or may be the same as the patented machine to which reference is made for details of construction not herein shown and described.

In order to center the sole, that is to locate it properly widthwise, after it has been located properly lengthwise by having its heel end thrust against the heel-end gage 15, two pairs of centering edge gages are provided, one pair 29, 30, which engages the edge of the sole 100 ahead of the heel-breast line, will be referred to as shank gages; and the other pair 31, 33, which engages the edges of the sole near the heel end, will be referred to as heel gages. The shank gage 29 and the heel gage 31 are pivoted about the smooth upper portion of a screw 35, the reduced lower end of which is threaded into a threaded hole 37 (Fig. 8) in an ear on the block 19. The shank gage 30 and the heel gage 33 are pivoted about the smooth portion of a similar screw 39 the lower reduced end of which is threaded into a threaded hole 41 in another ear of the block 19. The shank gages 29, 30 have respectively rear extensions 43, 45 which terminate in interengaging toothed segments 47, 49, so that the shank gages are compelled to swing equally in opposite directions. The heel gages 31, 33 have similar extensions which lie directly below the extensions 43, 45 and terminate in interengaging toothed segments which lie directly below the segments 43, 45. The extension 43 of the shank gage 29 is connected by a link 51 to one end of a whiffletree 53 which is pivoted at its middle at 55 to one end of a short link 57. A tension spring 61 connecting the pivot 63 of the link 51 with a short arm on the shank gage 29 normally holds the shank gages 29, 30 in the open position shown. A link 65 is pivoted at one end to the extension of the heel gage 33 and at the other end at 67 to the other end of the whiffletree 53; and a tension spring 69, connected at one end to the pivot 67 and at the other end 50 to an arm on the gage 33 normally holds the gages 31, 33 in the open position shown. The short link 57 at its right-hand end is pivoted about a horizontal pin 71 carried by the arms of a fork at the upper end of the upright arm of a bell-crank lever 73 pivoted at 75 to a bar 77. The inner end of this bar is rabbeted and fastened to the block 19 by cap screws 79. To the substantially horizontal arm of the bell-crank lever 73 is fastened the upper end of a two-part chain 60 81 the lower end of which is fastened to the treadle 27. The two parts of the chain are connected by a tension spring 85. When the treadle is depressed it exerts a pull on the chain and also pulls down a link 87 having a slot 88 in its upper end in which is received a pin 89. The first part of the downward movement of the treadle swings the bell-crank lever to pull the link 57 to the right and close the two pairs of gages on the sole, thereby centering the sole. All this takes place before the upper end of the slot 88 encounters the pin 89. Further downward movement of the treadle starts the machine through mechanism disclosed in the patent to Stewart referred to above.

Referring to Fig. 3, it will be seen that pulling the link 57 to the right will cause the two pairs of gages to close on the sole and that when the link 57 is released the springs 61, 69 will open the gages once more. In starting the machine the treadle is depressed and then released. In order to ensure that the gages shall remain in engagement with the sole until the table 23 has moved forward far enough so that the rolls 11, 13 have gripped the sole, there is pivoted at 91 to the right-hand end of the horizontal arm of the bell-crank lever 73 the lower end of a pawl 93 having a tooth which is held in engagement by a tension spring 99 with one or another of the teeth 97 of a rack formed on the right-hand end of the bar 77, the spring being attached at one end to the pawl 93 and at the other to the bell-crank lever 73. When the treadle is depressed, and the bell-crank lever 73 is swung clockwise, as viewed in Fig. 1, the pairs of edge gages are closed upon the sole and the springs 61, 69 are stretched. The pawl 93, however, prevents these springs from returning the parts to the positions shown in which the gages are open. It is necessary to release the pawl before the completion of a cycle of operations of the machine so that the gages will once more be open to receive the next sole. To this end use is made of the swinging to the left of the right-hand one of the links 25 upon the upper ends of which the table 23 is pivoted. An extension or tail is provided on the lower end of the right-hand link 25 which appears in Fig. 1, and to it is pivoted at 101 the lower end of a two-part push rod 103 the two parts of which are adjustably fastened together by two screw-and-slot 35 connections 105 so that the length of the rod may be varied. Upward movement of the push rod 103 actuates a slide member to release the pawl 93 and thereby permit the two pairs of gages to open. Referring to Figs. 6 and 9, this slide member or trip 107 has a slot 109 in its left-hand end to receive the pin 75 about which the bell-crank lever 73 is pivoted, and a second slot 111 in its right-hand end to receive the smooth portion of the stem of a screw 113 which extends through the 45 slot and is threaded into that part of the bar 77 on which the teeth 97 are formed. The slide member or trip has formed upon it a small projection 115 which is engaged by the top of the push rod 103 when the rod is moved up, such 50 engagement causing the trip 107 to slide to the right so as to push the pawl 93 away from the teeth 97 and permit the bell-crank lever 73 and the pawl 93 to return to the positions shown. The construction and arrangement of parts is such 55 that the pawl 93 holds the two pairs of gages in contact with the sole until the rolls 11, 13 have firmly gripped the sole, after which the pawl is pushed out of engagement with the teeth 97 and returns to the position shown. At the same time 60 the tension springs 61, 69 open the two pairs of gages to position them to receive another sole.

Referring now to Fig. 2, the gouge 200 and flap or tongue 300 are produced by distorting the shank portion of the sole and feeding it past a 65 stationary straight edged knife in such manner that the knife enters one face of the sole at the line 117 and emerges from it at the line 119, the knife in forming the gouge cutting along the line 121, thereby leaving the tongue 300 hinged to 70 the sole along one edge of the gouge in a narrow locality parallel to the line 121. To this end, the lower roll 11 (Fig. 7) is provided with spaced toothed disks 123 (Fig. 7), the two disks at each end of the roll being of comparatively large di- 75

ameter, and the six middle disks being of smaller diameter so that in effect a depression or sort of matrix is formed by their peripheries; and into this matrix or depression the shank portion 5 of the sole 100 is bent by a suitably shaped projection or patrinx 125 on the other roll 13. The right-hand end edge 127 of the knife 28 is outside of the sole and is cutting along the line 121 of Fig. 2. The left-hand end of the edge of the 10 knife is within the sole so that, when the cut is finished, the flap or tongue 300 will remain attached to the sole. The stem of the knife 28 (Fig. 3) extends obliquely to the axes of the rolls 11, 13 and is adjustably fastened to a block 15 129 by cap screws 131 which pass through slots in the knife stem and are threaded into the block. The block has in its under side a groove which is parallel to the axes of the rolls 11, 13; and in this groove is received the upper part of 20 a key 133 the lower part of which is received in a groove 135 in a wide bar 137 fastened by cap screws, one of which is shown at 139, to the frame of the machine. A clamping screw 141 extends up through an enlarged hole 143 in 25 the bar, through a hole in the key 133 and is threaded into the lower side of the block 129. The head of this clamping screw 141 appears in Fig. 1. With this construction, after the cap screws 131 have been loosened, the knife may be 30 adjusted obliquely to bring its cutting edge 127 into the desired position back of the bite of the rolls; and, after the clamping screw 141 has been loosened, the knife may be adjusted in a path 35 parallel to the axes of the rolls. In order to assist in properly replacing the knife (for example, after it has been removed and sharpened) a gage 145 pivoted at its rear end to the bar 137 has at its forward end a hook to engage the point at one end of the edge 127 of the knife 28. As 40 soon as the knife has been replaced and properly adjusted, this gage is swung out of the way. It may be noted (Fig. 3) that the cutting edge of the knife and one edge of the stem of the knife intersect at an acute angle to form a point at one end of the cutting edge of the knife.

45 In order to assist in holding the sole up against the patrinx roll 13, a series of spring-pressed fingers 147 (six being shown) are provided, the operative ends of which are located in grooves between the toothed disks 123 of the lower roll. 50 These fingers are pivoted about a stationary horizontal rod 149 and have downwardly extending stems which are normally held against a stationary rod 151 (Fig. 1) by tension springs one of which is shown at 153. When the sole is being operated upon (Fig. 5) these fingers press the sole upwardly against the roll 13.

55 The operation of the machine is as follows. With the parts of the machine in the positions of rest shown in Figs. 1 and 3, the operator thrusts a sole 100 through the gap between the rolls until its heel end contacts with the end gage 15. He thereupon depresses and then releases the treadle 27. The first part of the downward movement of the treadle swings the bell-crank lever 73 clockwise thereby causing the shank gages 29, 30 and the heel gages 31, 33 to close upon the sole. During this downward movement, the tooth of the pawl 93 runs over the teeth 97 of the stationary rack and holds the gages in closed position. 60 The latter part of the downward movement of the treadle 27, through the link 87, starts the machine. The links 25 swing to the left, as viewed in Fig. 1, to move the table 23 to the left in timed relation to the rotation of the rolls and

thereby present the sole properly to the rolls 11, 13. As soon as the rolls have properly gripped the sole, the table 23 returns to the position shown. During the forward movement of the table, when the links 25 swing to the left, the tail of the left-hand link 25 moves the push rod 103 up. The upper end of this rod (Fig. 9) encounters the projection 115 of the slide member 107 and moves this member to the right, thereby disengaging the pawl 93 from the teeth 97 and permitting the pairs of gages to be opened once more by the springs 61, 69. It will be noted, by reference to Fig. 7, that the point at one end of the edge of the knife 127 enters one face of the sole while said sole is distorted, remains in the sole for an interval and then emerges from the sole, but that the other end of the edge of the knife remains at all times entirely outside of the sole. The result is the production of the gouge 200 (Fig. 2) and the tongue 300 which is hinged to the sole along one edge of the gouge. In order to ensure that the sole shall be fed out from between the rolls after the gouge and the tongue have been produced, the upper roll 13 is provided with two ears, one of which is shown at 155 in Fig. 4. These ears engage the top of the sole and hold it against the lower roll.

Although the invention has been set forth as embodied in a particular machine, it should be understood that the invention is not limited in 30 the scope of its application to the particular machine which has been shown and described.

Having described my invention, what I claim as new and desire to secure by Letters Patent of the United States, is:

35

1. A machine for forming upon a piece of sheet material a gouge and a tongue which is hinged to the material along one edge of the gouge having, in combination, a pair of feed rolls and a knife to which the rolls feed the material, said rolls being 40 shaped to form a bulge in the material and to feed the bulged portion to the knife in such manner that one end of the edge of the knife enters one face of the material, remains in the material for an interval and then emerges from said face, 45 and the other end of the edge of the knife remains at all times outside of the material.

2. A machine for forming upon a piece of sheet material a gouge and a tongue which is hinged to the material along one edge of the gouge having, in combination, a pair of feed rolls, and a straight-edged knife to which the rolls feed the material, said rolls being shaped to form a bulge in the material and to feed the bulged portion to the knife in such manner that one end of the 50 edge of the knife enters one face of the material, remains in the material for an interval and then emerges from said face, and the other end of the edge of the knife remains at all times outside of the material.

3. A machine for forming upon a piece of sheet material a gouge and a tongue which is hinged to the material along one edge of the gouge having, in combination, a pair of feed rolls, and a straight-edged knife, said knife having a cutting edge which is substantially parallel to the axes of the rolls and a stem which extends obliquely to the cutting edge, one edge of the stem enclosing with the cutting edge of the knife an acute angle to form a point at one end of said cutting edge, 65 said rolls being shaped to form a bulge in the piece and feed it to the knife in such manner that the point at one end of the cutting edge enters one face of the material, remains in the material for an interval and then emerges there- 70 75

from, and the other end of the edge of the knife remains at all times outside of the material.

4. A machine for forming upon a piece of sheet material a gouge and a tongue which is hinged to 5
5. the material along one edge of the gouge having, in combination, a knife and a pair of rolls for feeding the material to the knife, one of said rolls having a projection and the other roll having spaced toothed disks of different diameters to 10
10 provide a depression into which the projection on the other roll bends the material to form a bulge therein.

5. A machine for forming upon a piece of sheet material a gouge and a tongue which is hinged to 15
15 the material along one edge of the gouge having, in combination, a knife and a pair of rolls for feeding the material to the knife, one of said rolls having a projection and the other roll having spaced toothed disks of different diameters to 20
20 provide a depression into which the projection on the other roll bends the material to form a bulge therein, one end of the edge of the knife being located to enter the bulge, to remain spaced from the surface of the material for an interval and 25
25 then to emerge from the surface, the other end of the edge of the knife remaining at all times outside of the material.

6. A machine for operating upon a blank having, in combination, a knife, a pair of rolls for 30
30 feeding the blank past the knife, a table movable toward and from the rolls to present the blank to the rolls, a pair of gages mounted on the table, said gages being normally open when the table is at rest, a treadle manipulation of which closes 35
35 the gages on the blank and locks them in closed position and then starts the machine, and means becoming operative after the rolls have gripped the blank for unlocking the gages and permitting them to open preparatory to receiving another 40
40 blank.

7. A machine for operating upon a blank having, in combination, a knife, a pair of rolls for feeding the blank past the knife, a table movable toward and from the rolls to present the blank to 45
45 the rolls, a pair of gages mounted on the table, said gages being normally open when the table is at rest, a treadle manipulation of which closes the gages on the blank and locks them in closed position and then starts the machine, and means 50
50 becoming operative after the rolls have gripped the blank and while the table is moving toward the rolls for unlocking the gages and permitting them to open preparatory to receiving another blank.

8. A machine for operating upon a blank having, in combination, a knife, a pair of rolls for feeding the blank to the knife, a table for presenting the blank to the rolls, said table being normally in retracted position, a pair of gages 60
60 for engaging a blank placed on the table, yielding means tending at all times to hold the gages open, treadle-controlled means for closing the gages on the blank and locking them in closed position, and means becoming operative while 65
65 the rolls are feeding the blank for unlocking the gages.

9. A machine for operating upon a blank having, in combination, a knife, a pair of rolls for feeding the blank to the knife, a table for presenting the blank to the knife, a pair of gages pivoted on the table for equal movement in opposite directions, yielding means normally holding the gages open, a member movement of which closes the gages in opposition to the force of the yielding means, means for moving the member into a position to close the gages, a pawl 10
10 for locking the member in its changed position, and means becoming operative during the operation of the machine for tripping the pawl to release the member and permit the gages to open. 15

10. A machine for operating upon a blank having, in combination, a pair of rolls having when at rest a gap between them through which the blank may be thrust in one direction, a knife past which the blank is fed in the other direction when the rolls are rotated, a pair of separable gages located on the opposite side of the rolls from the knife and adapted to receive the blank between them, means acting when the machine is at rest to hold the gages open, a table upon which the gages are mounted, means for causing the table to move toward the rolls to present the blank properly to the rolls and then to return to initial position, an operator-controlled member manipulation of which first closes the gages on the blank and locks them in 20
20 closed position and then causes the machine to operate, and means for becoming operative after the rolls have gripped the blank for unlocking the gages and permitting them to open preparatory to receiving another blank. 25
25

11. A machine for operating upon a blank having, in combination, a pair of rolls having when at rest a gap between them through which the blank may be thrust in one direction, a knife past which the blank is fed in the other direction when the rolls are rotated, a pair of separable gages on the opposite sides of the rolls from the knife and adapted to receive the blank between them, yielding means acting when the machine is at rest to hold the gages open, a 30
30 treadle manipulation of which starts the machine, closes the gages and locks them in closed position, and means becoming operative during the operation of the machine for unlocking the gages. 35
35

12. A machine for forming upon a piece of sheet material a gouge and a tongue which is hinged to the material along one edge of the gouge having, in combination, a pair of feed rolls shaped to distort the material, the axes of said 40
40 rolls being parallel, a knife for cutting the material while it is distorted, said knife having a cutting edge which is parallel to the axes of the rolls and a stem which is oblique to said cutting edge, and means for mounting the knife for adjustment in two paths one of which is parallel to the edge of the knife and the other of which is oblique to said edge. 45
